UNITED STATES PATENT OFFICE.

WILLIAM ROBERT SMITH, OF NEW YORK, N. Y.

AUTOMATIC WEIGHING-SCALE.

SPECIFICATION forming part of Letters Patent No. 375,102, dated December 20, 1887.

Application filed May 6, 1887. Serial No. 237,341. (No model.)

To all whom it may concern:

Be it known that I, WILLIAM ROBERT SMITH, a citizen of the United States, residing at New York, in the county of New York and State of New York, have invented certain new and useful Improvements in Automatic Weighing-Scales; and I do hereby declare the following to be a full, clear, and exact description of the invention, such as will enable others skilled in the art to which it appertains to make and use the same.

My invention relates to that class of scales in which the indicating mechanism is actuated by the fall of the rack-bar, released by trip mechanism such as shown in my application No. 214,501, filed September 25, 1886; and my invention relates more particularly to a chute or coin-receptacle through which the trip mechanism is operated by the momentum of a falling coin, and means for returning the indicator to zero or any desired point on the dial on the weight being partially removed from the platform of the scales.

My mechanism is adapted to ordinary platform weighing-scales, the platform being mounted upon any ordinary lever mechanism of such scales, and therefore I deem it unnecessary to illustrate such ordinary mechanism. Extending from the platform is an upright case, within which my mechanism is placed. Extending from the lever mechanism underneath the platform and up through the upright case is a rod or suitable connection, to the upper extremity of which the weighing-spring is connected. The upper end of this spring is suspended from a projection on the upper end of the metallic frame, which frame I secure to the back of the case in an upright position, as shown. On a standard or rod loosely pivoted to an offset on the upper extremity of the rod connecting the weighing-spring and the lever mechanism of the platform is secured a pivoted catch, which engages with a sleeve sliding on the standard and connected to a weight by a band passing over a pulley. Projecting from the sleeve is an offset or arm which engages with a cap on the front of the rack and serves both as a support and stop for the rack-bar which actuates the indicating mechanism. The rack-bar has a vertical motion in suitable bearings, its up motion being limited by a nut

at its lower end and its down motion by a cap which extends over the projecting arm of the sleeve when the latter is carried down by the descent of the rod-connection between the weighing-spring and the scale and its projecting standard. On the partial removal of the weight from the platform of the scales the connecting-rod rises with its standard, carrying with it the sleeve and the rack-bar suspended from the sleeve-offset. On the upward motion of the sleeve a pawl at the lower extremity of the catch which holds the sleeve engages with a rack, over which it passes freely in its descent, disengages the catch, and releases the sleeve, which is thus slid upward by the fall of the counter-weight, carrying with it the rack-bar back to its normal position. The up movement of the rack returns the indicator to zero, at which point the rack is locked in place by the latch. On the entire removal of the weight the moving frame, the standard, and its pivoted catch continue to rise until the latter again engages with the sleeve in order to carry it down at the next operation of the machine.

The coin-receiver and its releasing mechanism consist of a chute of suitable dimensions, into which projects one end of a pivoted lever, the other end of which engages with the rack-bar when the latter is in its normal position with the index at zero or other desired point. A coin introduced into the chute in its fall pushes aside the end of the lever, and thus withdraws the other arm from its engagement with the rack and releases it. The coin may be retained in the chute by a small lever until it is expelled by a crank-arm actuated by the return of the rack-bar to its first position, which trips the small retaining-lever.

In the accompanying drawings, which illustrate my invention, Figure 1 is a front view of the mechanism with the front of the case and dial removed. Fig. 2 is a side view of the same, partly in section, on the line *x y* of Fig. 1; and Fig. 3 is a view, partly in section, of the chute and latch with one side removed.

A is a rod, to the lower end of which the lever of the platform of the scales is attached, suspended from a projection on the upper part of the frame B by the spring C. A rod or standard, D, loosely pivoted to an offset on

- rod A at *a*, extends vertically upward and is supported in a suitable bearing, *d*, in which it slides freely, following the rise and fall of the lever-rod A. Pivoted to standard D at *d'* is 5 a catch, E, having a spring-tongue, *e*, secured to its base, but facing its upper hooked arm. A sleeve, F, sliding on standard D, has a cam, Fig. 1, of such shape that in passing between the hooked arm of catch E and spring *e* it 10 forces them apart until the hooked extremity of catch E, having risen above the cam, is interlocked with it by the continued pressure of spring *e* on the opposite side of the cam, and thus the sleeve is locked to the standard.
- 15 Catch E has at its lower extremity a pawl, *e'*, which yields readily when passing in a downward direction over a rack, H, but on the slightest up movement of standard D catches on the rack and pushes the catch E 20 out of engagement with sleeve F. The length of rack H is such that catch E in its downward motion never passes lower than the teeth on it, but can rise above it, so as to allow the spring *e* to engage with the sleeve F. Sleeve 25 F is suspended by a band, *g*, passing over a pulley, G, to a weight, *g'*, so that when it is released by the withdrawal of the catch E the weight carries the sleeve up until it is stopped by mechanism to be described farther on.
- 30 Extending from sleeve F is an arm or offset, I, which passes beneath and supports a cap, J, attached to the upper end of an independent rack-bar, K, which slides vertically in suitable bearings, *kk*. The rack-bar K is suspended 35 from the offset I in such wise that when not locked into place by the latch it falls with the descent of sleeve F when carried down by catch E, and is lifted by the rise of the sleeve until stopped by a nut, *k'*, on the 40 lower end of the rack-bar K abutting against the lower bearing *k*. In this way the limit of the up movement of the rack-bar K determines the distance sleeve F will ascend on standard D.
- 45 The latch mechanism by which rack-bar K is locked in position consists of a pivoted lever, L, having a horizontal motion, one arm of which, *l*, engages in a recess, *l'*, of rack-bar K when the latter is in its normal position, 50 while the other end, *l'*, projects slightly into a slot cut in the coin-chute M, Fig. 3, in such a way that a coin, N, of a given diameter, will in its fall push it aside, causing lever L to turn on its pivot and withdraw arm *l* from the notch 55 *l'* of the rack K, which will then fall until stopped by offset I on sleeve F. A pinion, F', meshing with the rack, turns the index-hand on the dial, thereby indicating the correct weight of the person standing on the platform.
- 60 Coin N falls through the chute M without being stopped, and may be received in any suitable receptacle below. After its passage lever L is pushed back into place by a spring, O, so that it is ready to lock the rack-bar K on 65 its return to its first position.

When it is desired to retain coin N in the chute after it has released the latch, I provide

a trip-lever, P, projected into the chute below lever-arm *l*', on which the coin rests and is supported until it is tripped and the coin allowed 70 to fall out by the action of the crank-arm Q, pivoted at *q* to a projection on the frame B. This arm Q rests loosely upon a pin, *q'*, on the rack-bar K and has a limited play up and down, its descent being stopped by a stud, *q''*, 75 and its rise being limited by that of the rack-bar. The face end of arm Q carries a tripping device, *q''*, which yields easily when passing lever P during the descent of the arm, but remains rigid and trips the lever P on its return, thus releasing the coin. 80

In the drawings I have shown standard D as a round rod. In this case sleeve F is prevented from turning on the rod by means of a pin, 1, traveling in a groove, 2, made in the 85 rod; but when the latter is square or of polygonal cross-section pin and groove are unnecessary.

The operation of my mechanism is as follows: In the absence of any weight upon the 90 platform of the scales the parts of the machine are in the position shown in Fig. 1, with rack-bar K locked in place, as shown. On placing a weight upon the scales, rod A and standard D descend, carrying down sleeve F in engagement with catch E, the pawl *e'* of the latter passing without obstruction over rack H. In its descent weight *g'* is lifted, but rack-bar K remains in place, being locked by its latch L. The weight is next indicated by introducing 95 a coin, N, into the chute M, which in its fall pushes aside arm *l*', releasing the rack-bar K, which falls until stopped by its cap J abutting against offset I of sleeve F, and the weight is indicated by the index-hand on the dial of the 100 machine. On the partial removal of the weight the rod A begins to ascend, causing the pawl to catch in rack H and push catch E out of engagement with sleeve F, which is then pulled up by the weight *g'*, and lifts with it 105 the rack-bar K, suspended from the offset I, until stopped by the nut *k'* on the lower end of the rack. The rise of the rack in pulling back the pinion, thereby turning the pointer-shaft, returns the pointer or index-hand to 110 zero or any desired point on the dial, at which point, which is the limit of the rise of the 115 rack, it is again locked by the latch P. On the entire removal of the weight, rod A and standard D continue to rise, and catch E swings 120 free of the rack H, being no longer pushed out by the sleeve and spring *e*, and rises until it again engages with the latter, ready for the next weighing. The advantage obtained by the return of the independent rack to zero on 125 the slightest removal of the weight from the platform prevents the successive weighing of two or more weights without additional payment.

It is evident that any equivalent yielding 130 connection may be substituted for the spring without affecting the operation of my invention; neither do I limit myself to its use with a spring alone.

I am aware that it is not new to use a pivoted segmental rack capable of a circular motion about its pivot; neither do I claim the same.

Having thus described my invention, what I claim as new, and desire to secure by Letters Patent, is—

1. In weighing-scales, the combination, with the indicating mechanism of the scales, of connecting mechanism between the spring and the

10 platform, a standard secured to the connecting mechanism, a sleeve sliding on the standard, connecting mechanism between the sleeve and indicating mechanism, and means for releasing the sleeve from the standard, whereby the connection between the standard and indicating mechanism is broken, substantially as described.

2. In weighing-scales, the combination, with the indicating mechanism of the scales, of connecting mechanism between the spring and platform, a standard secured to the connecting mechanism, a sleeve sliding on the standard, connecting mechanism between the sleeve and the indicating mechanism, and means independent of the spring and platform connections and standard for lifting the sleeve, whereby the indicating mechanism is operated independent of the rise of the spring and platform connections and of the stand-

30 ard, substantially as described.

3. In weighing-scales, the combination, with the indicating mechanism of the scales, of connecting mechanism between the spring and platform, a standard secured to the connecting mechanism, a sleeve sliding on the standard, connecting mechanism between the sleeve and indicating mechanism, means for releasing the sleeve from the standard, and means independent of the spring and platform connections for lifting the sleeve, whereby the indicating mechanism is actuated independently of the rise of the platform-connections and standard, substantially as described.

4. In weighing-scales, the combination, with the indicating mechanism of the scales, of connecting mechanism between the spring and platform, a standard secured to the connecting mechanism, a sleeve sliding on the standard, and a rack-bar suspended from the sleeve and engaging with the indicating mechanism, whereby the indicating mechanism is operated by the rise and fall of the sleeve and rack-bar suspended therefrom, substantially as described.

5. In weighing-scales, the combination, with the indicating mechanism of the scales, of connecting mechanism between the spring and platform, a standard secured to the connecting mechanism, a sleeve sliding on the stand-

50 ard, a rack-bar suspended from the sleeve and engaging with the indicating mechanism, means for releasing the sleeve from the stand-

ard, and means independent of the spring and platform connections for lifting the sleeve, whereby the indicating mechanism is actuated independently of the platform-connections and standard, substantially as described.

6. The combination of the vertically-sliding rack, the latch, and the chute whereby a coin dropped into the chute releases said rack by the momentum of its fall, substantially as described.

7. The combination of a vertically-sliding rack, the chute, the latch actuated by the momentum of the falling coin, the trip-lever extending in the chute for retaining the coin, and the pivoted crank-arm actuated by the rack, whereby the coin is released from the chute by the return of the rack, substantially as described, and for the purpose specified.

8. In weighing-scales, the combination, with the connecting mechanism of the spring and platform, of the standard secured to the connecting mechanism, a sleeve sliding upon the standard, means for automatically releasing the sleeve on the rise of the standard, means independent of the spring and platform connections for lifting the sleeve when released, a sliding rack suspended from the sleeve, and a latch operated by the momentum of a falling coin, substantially as and for the purposes hereinbefore set forth.

9. The combination of weighing-scales, a vertically-sliding rack, indicating mechanism, connecting mechanism between the rack and indicating mechanism, and means of holding the rack suspended independent of standard D, with its support, substantially as described.

10. The combination of a weighing-scale, connecting mechanism between the spring and the platform, a standard secured thereto, a rack, a sleeve on the standard engaging with the rack, indicating mechanism, connecting mechanism between the rack and indicating mechanism, and means for lifting the rack independent of the standard, substantially as described.

11. The combination, with weighing-scales, of indicating mechanism actuated by the descent of the scales, means for automatically releasing the indicating mechanism from its connection with the scales, and means independent of the weighing-scales for returning the indicating mechanism to its normal position, whereby on the descent of the scales the weight is indicated and the indicating mechanism then returned to zero, substantially as described.

In testimony whereof I affix my signature in presence of two witnesses.

WILLIAM ROBERT SMITH.
